US0D1052855S

(12) United States Design Patent (10) Patent No.: US D1,052,855 S
(45) Date of Patent: * Dec. 3, 2024

(54) BRASSIERE

(71) Applicant: Liang Zhan, Anqing (CN)

(72) Inventor: Liang Zhan, Anqing (CN)

() Term: 15 Years

(21) Appl. No.: 29/899,281

(22) Filed: Aug. 7, 2023

(30) Foreign Application Priority Data

Feb. 10, 2023 (CN) 202330042480.8

(51) LOC (14) Cl. 02-01

(52) U.S. Cl.

USPC D2/706; D2/708

(58) Field of Classification Search

(57) CLAIM

The ornamental design for a brassiere as shown and described.

DESCRIPTION

FIG. 1 is a perspective view of a brassiere worn on a body model showing the new design;

FIG. 2 is a front view thereof;

FIG. 3 is a rear view thereof;

FIG. 4 is a left side view thereof;

FIG. 5 is a right side view thereof;

FIG. 6 is a front view of the brassiere not worn on the body model; and,

FIG. 7 is a rear view of the brassiere not worn on the body model.

The broken lines represent the portions of the design that form no part of the claim. The broken line showing of a body model in FIGS. 1 through 5 is for the purpose of illustrating environment and forms no part of the claim.

1 Claim, 7 Drawing Sheets
